UNITED STATES PATENT OFFICE.

ELIAS R. GUERRA, OF HACIENDA DE SAN MATIAS, JALISCO, MEXICO.

ELEVATED CABLE RAILWAY.

SPECIFICATION forming part of Letters Patent No. 427,761, dated May 13, 1890.

Application filed February 18, 1890. Serial No. 340,944. (No model.)

To all whom it may concern:

Be it known that I, ELIAS R. GUERRA, of Hacienda de San Matias, State of Jalisco, Mexico, a citizen of Mexico, have invented 5 certain new and useful Improvements in Elevated Cable Railways, of which the following is a specification.

This invention relates to improvements in elevated railways, and especially to that class 10 in which the cars are suspended from the rails or tracks, and the object of my invention is to reduce the initial cost of the elevated railway, to facilitate stopping and starting the cars, and also to provide means for automatically 15 disengaging the cars from the cables at the crossings with other cables, and to automatically engage said car with the cable after said crossing cables have been passed.

The invention consists in the construction 20 and combination of parts and details, as will be described hereinafter, and finally pointed out in the claims.

In the accompanying drawings, Figure 1 is a side view of part of my improved elevated 25 railway. Fig. 2 is a cross-sectional view of the same, parts being broken out and the car being shown in cross-section on the line *xx*, Fig. 1. Fig. 3 is an enlarged transverse sectional view of the grip on a plane transversely to the 30 axis of the car. Fig. 4 is a vertical longitudinal sectional view of the same on the line *yy*, Fig. 3. Fig. 5 is a top view of the same, parts being shown in the horizontal section. Fig. 6 is a detail top view of the grip. Fig. 35 7 is a side view of the track at the crossings. Fig. 8 is a vertical transverse sectional view of the track, showing the device for supporting the cable and releasing the same when a car arrives. Fig. 9 is a detail side view of 40 the bar for operating the cable-supporting device. Fig. 10 is a sectional plan view on the line *ww*, Fig. 8. Fig. 11 is a detail view of the latch for locking the cable-supporting device. Fig. 12 is a detail end view of the 45 upper part of the car, showing the mechanism for applying the brake and opening the grip from said car.

Similar letters of reference indicate corresponding parts.

50 At suitable intervals supports or columns *A* are erected on the street and connected at their upper ends by transverse girders *A'*, ex-

tending across the street. To said transverse girders suitable hangers *A*² are secured, which support the longitudinal rails *A*³, which are 55 preferably made in the shape of an I-bar, but may have any suitable cross-section, and, if desired, may be made of lattice-work in the same manner as an ordinary girder.

The car *B*, which is of any well-known construction is provided at each end with a stirrup-shaped hanger *B'*, firmly secured to the car and provided at its center with an upwardly-projecting hanger-bar *B*², having a slot *B*³, through which the main axle *C* passes 60 freely, on the ends of which axle the flanged wheels *C'* are mounted. Said hanger-bar *B*² is thus adapted to move up and down in relation to the axle *C*, which at all times maintains its position in relation to the rails. (See 65 Fig. 4.) A short distance below the axle *C* the hanger-bar *B*² is provided with an additional fixed axle *D*, on the ends of which smaller wheels *D'* are mounted, said wheels *D'* being adapted to run on bracket-rails *D*², 70 secured on the inner sides of the main rails *A*³, as will be hereinafter described.

A frame *E* is mounted on the main axle *C*, and on the upper end of the same the two jaws *E'* are pivoted, which jaws are provided 80 on the ends below the pivots with anti-friction rollers *E*². One of said jaws carries two gripping-rollers *E*³ and the other jaw a single gripping-roller *E*³, said rollers being so arranged that the single roller *E*³ on one jaw is 85 between the two rollers on the other jaw. In front and behind the jaws *E'* transverse guide-rollers *E*⁴ are mounted on the top of the frame *E*. The hanger-bar *B*² is provided at its upper end with a wedge-shaped head *F*, 90 that can act on the anti-friction rollers *E*³ on the lower ends of the jaws *E'*.

The frame *E* is provided at its lower end with brackets *G*, to which arms *G'* are pivoted, an axle *G*² being mounted to turn in 95 the swinging ends of said arms. On said shaft or axle *G*² two wheels *G*³ are rigidly mounted above the rails *A*³, so that by pressing them downward they can come in contact with the upper surfaces of said rails. On 100 those ends of the shaft or axle *G*² projecting beyond the outer sides of the wheels *G*³ are loosely mounted smaller friction-wheels *G*⁴, that can come in contact with vertically-mov-

able rails H, arranged above them, which rails are connected by bow-shaped or other springs H' with rods H², the upper ends of which surround eccentric disks H³, fixed on a shaft H⁴ 5 on the hanger or frame of the elevated railway, and which can be rotated from the station by means of the beveled gearing H⁵ and rods H⁶.

A brake-shoe I, which is segmental in shape 10 and provided with curved wings I' and a bearing-bar I², is arranged above each wheel C', the brake-shoes of the opposite wheels being connected by arms C², as shown in Fig. 5. A lever J is pivoted on the hanger-bar B², and 15 is provided on its lower end with a cam J', resting on the axle C, adjacent to said cam J'. The bar J is provided with a smaller cam J², that can act on the bearing-bar I² of one brake-shoe I so as to press the tops of the 20 brake-shoes upon the wheel-rims. The arms J of the front and rear hanger of the car are connected to the rod J³. One end of a rope or chain K is fastened to the upper end of the arm J, at the front end of the car, and 25 the other end of said rope or cable is secured to the axle G². A spring K', secured to the bottom of the frame, bears against the arms G', pivoted to the brackets G, and presses them upward, thereby holding the rims of the 30 wheels G³ slightly above the tops or heads of the rails A³. The brackets G, arms G', and axle or shaft G² need only be provided at the front end of the bar.

As shown in Fig. 12, the axle G² is connected by a rope or chain K³ with a transverse shaft K⁴ on the top of the car, which shaft K⁴ can be rotated by means of beveled gearing K⁵ and a vertical shaft K⁶ on the front end of the car.

40 The bracket-rail D² is only provided a short distance each side of every crossing, said rail D² running horizontally, whereas the top of the main rail is inclined downward from both sides of the station toward said 45 crossing, as shown in Fig. 7, where X represents the swinging part of the track of the crossing. The bracket-rail D² runs horizontally throughout. The reason for arranging the main rails and the bracket-rails in this 50 manner will appear hereinafter. The cable M is supported by a series of L-shaped hangers M', each fixed on a shaft M² in the frame M⁵, and said hangers are provided on their swinging ends with grooved rollers M³, on 55 which the cables rest. The arm M⁴ of each hanger M' is provided on its end with a laterally-projecting pin N and with a spur N' projecting in the direction of the length of said arm. The weight of the cable presses 60 said spur against a bolt O, mounted to slide in a suitable casing O' on the frame of the structure, which bolt is pressed in the direction toward the cable by a spring O². The pin N passes through a longitudinal slot P' 65 in the upper end of a vertical connecting-bar P, the lower end of which is pivoted to the longer end of a lever P², pivoted at P³ to the

frame M⁵. The shorter end of the lever P² rests against the bottom edge of a rail Q, pivoted to the upper ends of a pair of links Q', 70 the lower ends of which are pivoted to the outer surface of the main rail A³, said links being connected by a rod Q², so as to form a parallelogram. Springs Q³ acting on the links Q', serve to keep the rail Q in the raised position and a short distance above the top of the main rail A³, as shown in Figs. 8 and 9. 75

The connecting-bar P is provided at its upper end with a tapered and rounded lug P⁴, that can act on the tapered or rounded bottom edge of the bolt O and press said bolt in the direction from the cable. 80

S represents a bracket, which is suitably pivoted, and on the free end of the same an upright guide-roller S' for the cables is provided, said brackets being arranged at curves. 85

The shaft M², on which the hanger M' is fixed, is provided with an arm T, carrying a counterbalancing-weight T', for the purpose of assisting in supporting the cable. 90

The operation is as follows: Ordinarily the top of the slot B³ in the hanger-bar B² of the car rests on the top of the axle C, so that the weight of the car is thus transmitted from the hanger-bar B² to the axle, from the axle to the 95 wheels, and from the wheels to the rails. The sides of the wedge-shaped head F on the upper end of the hanger-bar B² press outward the lower ends of the jaws E', thereby pressing the upper ends of said jaws inward and toward each other, and in turn pressing the gripping-rollers E³ E³ against the cable M, so that as said cable moves it draws along the grip on the car. When the car arrives at 100 a crossing, the cable must be released and the gripping-jaws move out of the way, so as not to interfere with the crossing cable. As has been stated, and as shown in Fig. 7, the tops of the main rails are inclined from both sides toward the crossing, and consequently the wheels on the axle C can run downward while approaching the crossing. As soon as the inclination of the main rail begins, the wheels D' run on the bracket-rails, and thus keep the car and hanger-bar 110 in the same position—that is, it prevents them from running downward toward the crossing. The wheels C' and the axle C, however, run downward on the inclined main rails, and thereby the frame E is lowered in 115 relation to the hanger-bar B². The anti-friction rollers E² of the gripping-jaws E' thus move downward in relation to the wedge-shaped head F of the hanger-bar, and as said wedge-shaped head no longer acts upon them 120 they swing downward and outward under the action of their own weight, thereby releasing the cable, as shown in dotted lines in Fig. 3. When swinging down, the gripping-jaws E' are so low as to easily pass under the 125 crossing cable. As the wheels leave the crossing, they run up the inclined track, whereby the frame E is raised in relation to the hanger-bar B², and the anti-friction rollers 130

E² on the lower ends of the gripping-jaws E' are again forced outward by the action of the wedge-shaped head F of said hanger-bar B² on said rollers, and the jaws are brought 5 back into the position shown in Fig. 3 and securely grip the cable. The car always runs on in the same level and it is only the frame E and the gripping-jaws that move vertically. Ordinarily the weight of the car is support to 10 the main axle C; but at such crossing—that is to say, as long as the main track is inclined toward said crossing—the weight of the car is supported by the supplementary axle D.

15 When a train is to be stopped at a station, the station-master turns the shaft H⁴ by means of any suitable contrivance in such a manner as to move the rods H² H² downward, causing the springs H' to press down the 20 bars H, which are pivoted at one end and connected at the opposite end with said springs H'. The bars H, when moved downward, are pressed against the rims of the wheels G⁴, said wheels G⁴ being loose on the 25 ends of the shaft G². Thereby the axle G² is pressed downward sufficiently to bring the wheels G³ in frictional contact with the main rails, whereby said wheels G³ and axle G² are so rotated as to wind the chain or rope K on 30 said axle G². Thereby the arm J is swung in the direction of the arrow x', Fig. 4, and the cam J', acting on the top of the transverse axle C, causes an upward movement of the pivot of the cam and of the hanger-bar B², to 35 which the cam is pivoted.

By moving upward the hanger-bar B² the anti-friction rollers E² on the lower end of the gripping-jaws E' are relieved from the pressure exerted by the wedge-shaped head F and 40 the jaws separated, thereby releasing the cable. At the same time the cams J² act on the bearing-bars I² of the brake-shoes I and press said brake-shoes against the rims of the 45 wheels C'.

45 As the cable is released and the brake-shoes powerfully applied on the wheel-rims, the car is stopped in a very short time and remains at a standstill as long as the rail H is pressed downward.

50 When it is desired to start the car, the shaft H⁴ is turned in such a manner as to move the rods H² upward, whereby the rails H are raised, thus permitting the springs K' to throw the arms G' upward and bring the wheels G³ out 55 of contact with the main rails. The weight of the car acting on the cam J' throws the upper end of the arm J in the inverse direction of the arrow x', and at the same time the hanger-bar B² is lowered under the action 60 of the weight of the car, and its wedge-shaped head F, forcing the lower ends of the gripping-jaws from each other, forces the upper ends of said jaws against the cable which is thus gripped. The car can thus be stopped 65 automatically by the station-master by simply adjusting the rails H correspondingly.

In some cases it becomes necessary to stop

the trains between the stations to avoid a collision, and in order to do this one of the trainmen turns the shaft K⁴ in such a manner as 70 to wind the rope K³ upon it, whereby the wheels G³ are brought in contact with the rails A³, and the arm J is also moved in the direction of the arrow x', Fig. 4, and the cam J' raises the hanger-bar B², whereby the gripping-jaws are disengaged from the cable and the brake-shoes are applied. 75

The cable is ordinarily suspended from the hangers M', which, however, must be brought out of the way when a car passes. At each 80 supporting-lever M' a rail Q is arranged. When the front wheels of the car run upon said rail Q, they depress the same, and also depress the shorter end of the corresponding lever P², whereby the bar P, connected with 85 the same, is raised.

The lug P⁴ on the upper end of the bar P acts on the bolt O and pushes the same in the direction of the arrow y', thereby releasing the spur N', which by the weight of the 90 cable was pressed against the bottom edge of said bolt. That end of the hanger M' supporting the cable now swings under the action of the weight of said cable in the direction of the arrow x², so as to be out of the 95 way of the grip. As long as the car passes, the rail Q remains depressed and the lever M' is in lowered position. As soon as the last wheel of the car has passed, the weight of the bar P and the counter-weight T' swings 100 the hanger M' in the inverse direction of the arrow x², whereby the roller M³ is brought under and supports the cable again. When the lever M' swings in the inverse direction of the arrow x² under the action of the weight 105 of the bar P and the counter-weight T', the bottom bevel of the lug P⁴ strikes the top bevel of the bolt O and pushes said bolt to the right, so as to permit the lug N' to pass below said bolt, and the weight of the cable acting 110 on the hanger M' presses said lug N' against the bolt O.

If the bolt O were not provided, the hanger M' could not support the cable, as it would always be in the lowered position, and it is 115 the said bolt that keeps the hanger M' in the proper position for supporting the cable.

Having thus described my invention, I claim as new and desire to secure by Letters Patent—

1. The combination, with the rails of a railway-track having its upper surface inclined from both sides to a gap or crossing, of horizontal rails projecting laterally from the inner surfaces of the track-rails, substantially 125 as set forth.

2. The combination, with a railway-track, of a pivoted cable support or hanger, a rail arranged at the side of the track-rail and levers or rods for transmitting motion from said 130 side rail to the cable support or hanger, substantially as set forth.

3. The combination, with a railway-track, of a pivoted cable support or hanger, a latch

for locking said support in place, a rail at the side of the track-rail, and rods and levers for transmitting motion from said side rail to the cable support or hanger and its latch, substantially as set forth.

4. The combination, with a railway-track, of a pivoted cable support or hanger and a rail arranged at the side of a track-rail, springs pressing said side rail above the top of the track, a pivoted lever, on one end of which said side rail rests, and a bar connecting said lever with the above-mentioned cable hanger or support, substantially as set forth.

5. The combination, with a railway-track, of a pivoted cable support or hanger, a counter-weight connected with the same, a rail arranged at the side of the track-rail, and levers and rods for transmitting motion from said rail to the said pivoted support, substantially as set forth.

6. The combination, with a railway-track, of a pivoted cable support or hanger, a latch for locking said support in place, and a bar for moving said support or hanger, which bar is provided with a projection adapted to act on the above-mentioned latch, substantially as set forth.

7. The combination, with a car, of a hanger-bar and an axle provided with wheels, said hanger-bar being adapted to move vertically in relation to said axle, substantially as set forth.

8. The combination, with a car, of a hanger-bar, an axle carrying wheels, a frame on said axle, and gripping-jaws at the upper end of said frame, on which said gripping-jaws the upper end of the hanger-bar can act, substantially as set forth.

9. The combination, with a car, of a hanger-bar and an axle carrying wheels, a frame on said axle, gripping-jaws pivoted to said frame and provided on their lower ends with anti-friction rollers, and a wedge-shaped head on the upper end of said hanger-bar, which wedge-shaped head can act on the anti-friction rollers on the lower ends of said gripping-jaws, substantially as set forth.

10. The combination, with a car, of a hanger-bar having a slot, an axle passed through said slot, wheels on said axle, a frame mounted on said axle, gripping-jaws pivoted to the top of said frame, a head on the upper end of the hanger-bar adapted to act on said jaws, an auxiliary axle fixed in the hanger-bar, and wheels mounted on said auxiliary axle, substantially as set forth.

11. The combination, with track-rails, of bracket-rails projecting from the sides of the same, a car, a hanger-bar on said car, which hanger-bar is provided with a slot, an axle passed through said slot and provided with wheels running on the track-rails, a frame on said main axle, gripping-jaws pivoted to the upper end of said frame, a head on the hanger-bar adapted to act on said jaws, an auxiliary axle on said hanger-bar, and wheels on

1 said auxiliary axle, which wheels run on the bracket-rails, substantially as set forth.

12. The combination, with a car, of a hanger-bar, an axle passed through a slot in said hanger-bar and provided with wheels on its ends, a cam pivoted on the hanger-bar and resting on said axle, and means for turning said cam, substantially as set forth.

13. The combination, with a car, of a hanger-bar, an axle passed through a slot in the hanger-bar, a cam pivoted to the hanger-bar and resting on the axle, an additional cam projecting from the above-mentioned cam, and brake-shoes on which the additional cam can act, and means for turning said cams, substantially as set forth.

14. The combination, with a car, of a hanger-bar, an axle passed through a slot in the hanger-bar, a cam pivoted to the hanger-bar and provided with an arm, a frame mounted on the axle, arms pivoted to said frame, a shaft mounted in said arms, friction-wheels on said shaft, and a chain or rope connecting said shaft with the arm of the cam, substantially as set forth.

15. The combination, with a car, of a hanger-bar, an axle passed through a slot in the hanger-bar, a cam pivoted to the hanger-bar and provided with an arm, a frame 95 mounted on the axle, arms pivoted to said frame, a shaft mounted in said arms, friction-wheels on said shaft, and a chain or rope connecting said shaft with the arm of the cam, and a rail for pressing the friction-wheels in contact with the main rails, substantially as set forth.

16. The combination, with a car, of a hanger-bar, an axle passed through a slot in the hanger-bar, a cam pivoted to the hanger-bar and provided with an arm, a frame mounted on the axle, arms pivoted to said frame, a shaft mounted in said arms, friction-wheels in said shaft, a chain or rope connecting said shaft with the arm of the cam, a rail 110 for pressing the friction-wheels in contact with the main rails, an eccentric, and a rod and spring for adjusting said rail from said eccentric, substantially as set forth.

17. The combination, with a car, of a hanger-bar, an axle passed through a slot in the hanger-bar, a cam pivoted to the hanger-bar and provided with an arm, a frame mounted on the axle, arms pivoted to said frame, a shaft mounted in said arms, friction-wheels on said shaft, a chain or rope connecting said shaft with the arm of the cam, a rail for pressing the friction-wheels in contact with the main rails, an eccentric, a rod, and a spring for operating said rail from said eccentric, and gearing for operating said eccentric, substantially as set forth.

18. The combination, with a car, of a hanger-bar, an axle passed through a slot in the hanger-bar, a frame mounted on said axle, arms pivoted to said frame, a shaft mounted in said arms, friction-wheels on said

shaft, loose wheels on the ends of the shaft, a rail above said loose wheels, and means for pressing down said rail, thereby pressing the friction-wheels on the shaft against the main rails, substantially as set forth.

19. The combination, with a car, of a hanger-bar, an axle passed through a slot in the hanger-bar, a frame mounted on said axle, arms pivoted to said frame, a shaft mounted in said arms, friction-wheels on said shaft, loose wheels on the ends of the shaft, a rail above said loose wheels, means for pressing down said rail, thereby pressing the fric-

tion-wheels on the additional axle against the main rails, and springs for pressing said arms 15 and the shaft mounted in the same upward and clear of the main rails, substantially as set forth.

In testimony that I claim the foregoing as my invention I have signed my name in presence of two subscribing witnesses.

ELIAS R. GUERRA.
